UNITED STATES PATENT OFFICE

2,568,985

WINDOW CONSTRUCTION

Theron F. Brenneman, Elkhart, Ind., assignor to
 The Adlake Company, Chicago, Ill., a corpora-
 tion of Illinois

Application June 10, 1947, Serial No. 753,610

2 Claims. (Cl. 20—52.4)

1

This invention relates to improvements in window constructions.

In the type of window construction which comprises a frame and sash members formed from extruded metal, such as aluminum, it is difficult to obtain a satisfactory weatherproof construction which will prevent leakage between the side frame member and the ends of the sash meeting rail at the point where the meeting rails are positioned relative to the side frame member when the window is in closed condition. In ordinary constructions the end of the sash meeting rail is spaced from the side frame member to allow sufficient clearance for the free vertical movement of the sash. This space between the end of the meeting rail and the side frame member permits passage of water and dirt upwardly from the outside of the window and into the interior.

It is an object of the invention to provide a window construction wherein a weather block is permanently secured to the side frame member at the point where the ends of the sash meeting rails are positioned when the window is in closed condition, which block is so constructed that it does not interfere with the movement of the sash but at the same time fills the space between the ends of the meeting rails and the frame and prevents the passage of water and dirt therethrough.

These and other objects will be apparent from a description of the preferred form of the invention which is shown, by way of illustration, in the accompanying drawings, wherein:

Fig. 1 is a perspective view of a portion of a window construction embodying the principles of the invention, the bottom movable sash being omitted;

Fig. 2 is a section on the line 2—2 of Fig. 1, with the bottom movable sash in closed position;

Fig. 3 is a section on the line 3—3 of Fig. 2;

Fig. 4 is a section on the line 4—4 of Fig. 1;

Fig. 5 is a perspective view of the weather block member; and

Fig. 6 is a perspective view of the retaining clip for the weather block member.

The invention is illustrated in the drawings in connection with a window construction of the type having an upper fixed sash and a lower movable sash wherein one meeting rail is rigidly joined at its ends to the side frame members to form the bottom of the fixed sash while the other meeting rail forms the top rail of the movable sash which is slidable vertically in side guide channels provided in the side frame members. Only one side of the window is illustrated. It will be understood that the construction will ordi-

2

narily be incorporated in both sides of the window. The lower movable sash is not shown in Fig. 1. It is shown in the closed position in Figs. 2 and 3.

5 In the construction shown, the side frame or jamb member 10 is formed from an extruded metal section to provide an inner guide channel forming portion 11 for reception of a sliding sash and an outer portion 12, the upper half of which 10 constitutes the side member of a fixed sash. The horizontal meeting rail 13 forms the bottom member of the fixed sash and is rigidly joined at its end to the side frame member 10. The portion 12 of the side frame 10 and the meeting rail 13 are constructed to provide a glazing channel 14 for reception of one or more panes of glass (not shown). The meeting rail 13 is provided with a groove 15 for receiving a glazing strip (not shown) to secure the panes of glass in the channel 14. 15 The meeting rail 13 includes an inner face plate 16 and a channel formation 17 for cooperating with portions of the meeting rail on the movable sash. 20 The inner portion 11 of the frame member 10 includes an inside face plate 18 and an oppositely disposed flange portion 19 connected adjacent their outer edges by a web portion 20 forming a side guide channel 21 in which the vertical side member 22 of the movable sash 23 is received. 25 The inner portion 11 of the side frame member 10 is connected to the outer fixed sash forming portion 12 by an intermediate web member 24 which extends to the inner face plate 25 of the portion 12 and is integrally joined along one side 30 thereto in angular relation, forming a vertical recess or corner.

The movable sash 23 includes the vertical side member 22 and a top or meeting rail 26 which are joined at their ends in abutting relation. The 35 meeting rail 26 is provided with an outer portion 27 forming a downwardly opening channel which is adapted to receive the upper portion of the face plate 16 on the meeting rail 13 when the sash is in closed condition. Weather strip carrying members 28 are secured in the channel portion 27. The meeting rail 26 is secured to the side member 22 in any conventional manner to provide a rigid frame. The meeting rail 26 and the side member 22 are provided on their inner 40 sides with a glazing channel 29 for receiving one or more panes of glass (not shown) and a groove 30 for receiving a glazing strip (not shown) to secure the glass panes in position. The end of the meeting rail 26 is cut away at 31 to provide 45 clearance for free vertical movement of the sash 50 55

and the side member 22 is provided with a weather-strip member 32.

The fixed meeting rail 13 is cut at its end 33 so that the inner portion thereof including the face plate 16 is spaced from the web portion 24 of the vertical side frame member 10 when the members are in assembled relation.

A weather-strip block 34 of felt, or similar material, and of the shape illustrated in Fig. 5 is provided which is adapted to be positioned between the end of the meeting rails 13, 26 and the vertical face of the side frame member 10. The inner face 35 of the block 34 is beveled at the ends 36 and 37 while the outer face 38 is provided with a flanged portion 39 extending along the inside edge. The block 34 is of sufficient transverse cross section to substantially fill the space between the end 33 of the meeting rail 13 and the adjacent portions 24 and 25 of the side frame member 10 and is positioned with the flanged edge portion 39 extending outwardly along the inner face of the portion 19 of the frame member 10.

A holding clip member 40 is provided for securing the block 34 in position on the web portion 24. The member 40 is preferably made of a relatively flat hard metal, such as stainless steel plate, and comprises an intermediate portion 41 terminating in beveled end portions 42 and 43. One end 42 is provided with an angular lug or extension 44 of reduced width. The other end 43 is provided with a flat lip or extension 45 which is in parallel offset relation to the intermediate portion 41 and which is provided with an aperture 46.

The web portion 24 of the frame 10 is provided with a transverse slot 47 above the block 34 which is adapted to receive the angular lug member 44 of the holding clip 40 in interengaging relation. A tapped hole 48 is provided in the web portion 24 at a spaced distance below the slot 47 for reception of a threaded screw 49 by means of which the holding clip 40 is secured in position. The portion 41 of the clip 40 is in abutting relation with the end 33 of the fixed meeting rail 13. The weather block 34 completely fills the space in the corner between the end 33 of the fixed meeting rail 13 and the portions 24 and 25 of the side frame 10 and extends laterally inwardly a sufficient distance to fill the space between the end 31 of the movable meeting rail and the portion 24 of the side frame member 10 when the sash 23 is in closed position. The flanged portion 39 of the block 34 extends into the side guide channel 21 and cooperates with the weather-strip member 32 to fill up the small space between the sash side member 22 and the portion 19 of the side frame member 10.

The novel construction is illustrated in the drawings as incorporated in a window having a frame provided with a top fixed sash portion and having a lower movable sash mounted in sliding relation therein. The construction is also applicable to a double-hung sash type window wherein the meeting rails are both movable relative to the side frame or jamb member. The weather-strip block is positioned in the double-

hung sash type window so that it fills the space between the ends of the meeting rails and the adjacent side frame member when the sash are in closed condition.

While specific details of construction and materials have been referred to in describing the illustrated form of the invention, it will be understood that other details of construction and other materials may be resorted to within the spirit of the invention.

I claim:

1. In a window construction having a vertical side frame member and sash members provided with horizontal meeting rails, end portions of the meeting rails being spaced from the side frame member, a weather strip comprising a relatively short length of compressible strip material having beveled ends and a side flange portion, said strip material being adapted to be positioned between the end portions of the meeting rails and the side frame member when the window is in closed condition, and a steel clip member for securing said strip material to the side frame member, said clip having beveled end portions for accommodating the ends of said strip material, an angular extension on one end of said clip for detachably engaging in a slot in said side frame member and an aperture on the other end of said clip for receiving a securing screw to permanently fasten said strip to the side frame member.

2. In a window construction having upper and lower sash members and side frame members provided with vertical guideways for the lower sash member, said sash members having meeting rails which extend between said side frame members and which are spaced at the ends from said side frame members, a weather strip comprising a felt block and a hard metal securing plate member adapted to be positioned between the ends of the meeting rails and the adjacent side frame member to fill the space therebetween when the window is in the closed condition, said felt block having beveled ends and a side flange portion, said side flange portion being adapted to extend into the guideway for said lower sash, said securing plate member having beveled ends conforming to the beveled ends of said felt block, one of said beveled ends having a hook formation for engagement in a slot in the side frame member and the other of said ends having a removable fastening screw for securing the same in fixed relation on the side frame member.

THERON F. BRENNEMAN.
